PHOTOGRAPHIC PRINT CROPPER

Mark J. Klayman, 75 Henry St.,
Brooklyn, N.Y. 11201

Filed July 10, 1972, Ser. No. 270,266

Term of patent 14 years

Int. Cl. D16—99

U.S. Cl. D61—1 P

FIG. 1.

FIG. 2.

FIG. 3.

FIG. 4.

FIG. 5.

FIG. 7.

FIG. 6.

FIG. 1 is a top plan view of a photographic print cropper, showing my new design;

FIG. 2 is a bottom plan view thereof;

FIG. 3 is a front elevational view thereof;

FIG. 4 is a rear elevational view thereof;

FIG. 5 is a left side elevational view thereof, the right side being the mirror image thereto;

FIG. 6 is a cross-sectional view of FIG. 1 as taken from line 6—6; and

FIG. 7 is a top plan view of another embodiment of my new design wherein the proportional guide is rectangular rather than square.

I claim:

The ornamental design for a photographic print cropper, substantially as shown and described.
